UNITED STATES PATENT OFFICE.

JOHN W. OTTO, OF ALTOONA, PENNSYLVANIA.

CHURN.

SPECIFICATION forming part of Letters Patent No. 605,649, dated June 14, 1898.

Application filed September 25, 1897. Serial No. 653,034. (No model.)

To all whom it may concern:

Be it known that I, JOHN W. OTTO, a citizen of the United States, residing at Altoona, in the county of Blair and State of Pennsylvania, 5 have invented certain new and useful Improvements in Churns; and I do declare the following to be a full, clear, and exact description of the invention, such as will enable others skilled in the art to which it appertains to 10 make and use the same, reference being had to the accompanying drawings, and to the letters of reference marked thereon, which form a part of this specification.

This invention relates to certain new and 15 useful improvements in churns; and it relates more particularly to that class of churns in which two rotating dashers are provided, one of the dashers being adapted to rotate in one direction and the other in the opposite.

20 The invention has for its object the provision of a churn of the character referred to in which a concave and a convex dasher are employed, the concave dasher being provided with spirally-arranged recesses and the other dasher, which has a convex surface, being provided with a series of spirally-arranged wings corresponding in number and relative arrangement with the depressions formed within the concave surface of the lower 25 dasher.

30 A further object of the invention resides in the means employed, whereby the relative positions of the dashers may be quickly and easily adjusted.

35 To these ends and to such others as the invention may pertain the same consists in the novel construction and in the peculiar arrangement, combination, and adaptation of parts, all as more fully hereinafter described, 40 shown in the accompanying drawings, and then specifically defined in the appended claim.

The invention is clearly illustrated in the 45 accompanying drawings, which, with the letters of reference marked thereon, form a part of this specification, like letters of reference indicating the same parts throughout the several views, and in which drawings—

50 Figure 1 is a front elevation, partly in section, of a churn constructed in accordance with my invention. Figs. 2 and 3 are top and bottom plan views, respectively, of the upper

or convex dasher; and Figs. 4 and 5 are top and bottom plan views, respectively, of the lower or concave dasher.

55

Reference now being had to the details of the drawings by letter, C is the churn-body, which may be constructed of any suitable material and of any desired size.

D is a vertical shaft which is stepped at its 60 lower end within suitable bearings, and its upper portion passes through eyes formed in the metallic frame E E. This shaft has keyed thereto at its lower end a concave dasher B, which is provided with a series of depressed 65 recesses F F and has external blades or rings B' thereon, and at the upper end the said shaft is provided with a beveled pinion G, which meshes with a beveled gear-wheel H upon the shaft I, to the outer end of which shaft a suitable operating-crank J is attached.

A represents the upper dasher, which is relatively of the same diameter as the diameter of the lower dasher B, the said dasher A being, however, convex in form and having 75 its outer surface provided with a series of spirally-arranged wings K, corresponding in size, number, and relative arrangement with the depressions F in the concave dasher B. The dasher A is keyed to a hollow shaft L, 80 the upper end of which shaft is provided with a beveled pinion M, which meshes with the beveled gear-wheel H. By this construction it will be seen that the rotation of the wheel H will cause the dasher B, which is carried 85 upon the lower end of the shaft D, to rotate in one direction, while the dasher A, attached to the outer tube L, will be rotated in the opposite direction. The dasher B is adjustably connected to the lower end of the shaft D by 90 means of a set-screw a, which is passed through a collar b and bears against the surface of this shaft, while the dasher A, which is carried by the hollow shaft L, is in like manner adjustably connected to the shaft by 95 means of a set-screw c, passed through a collar d. It will be seen that by this construction the relative positions of the dashers may be readily varied as occasion may require.

The rapid rotation of the dashers in opposite directions produces a powerful suction, and the oppositely-disposed depressions and wings will serve to effectually break up the butter-cells in the cream. The agitation of

the cream thus produces results in the making of butter within a very short period of time, thus saving a great amount of time and labor.

Having thus described my invention, what 5 I claim to be new, and desire to secure by Letters Patent, is—

In a churn, the combination with the operating-shafts and bowl-shaped dasher A, which has a series of spirally-arranged scalloped recesses about its outer wall, the dasher B, which is concaved and provided with a series

of spirally-arranged scalloped recesses F in its interior wall, with ridges between said scallops, and the blades B' about the outer surface of said dasher B, as shown and described.

In testimony whereof I affix my signature in presence of two witnesses.

JOHN W. OTTO.
